UNITED STATES PATENT OFFICE.

MILO B. HINER, OF ALEXANDRIA, SOUTH DAKOTA.

SPRING STANCHION-LOCK.

1,071,316.

Specification of Letters Patent.

Patented Aug. 26, 1913.

Application filed September 16, 1912. Serial No. 720,636.

To all whom it may concern:

Be it known that I, MILO B. HINER, a citizen of the United States, residing at Alexandria, in the county of Hanson, State 5 of South Dakota, have invented certain new and useful Improvements in Spring Stanchion-Locks; and I do hereby declare the following to be a full, clear, and exact description of the invention, such as will 10 enable others skilled in the art to which it appertains to make and use the same.

This invention relates to stanchions and more particularly to spring locks thereof.

The object of the invention is to provide 15 a spring lock mechanism, whereby a stanchion may be readily and securely locked in closed position.

Another object is to provide a spring lock of this character formed of two pieces of 20 metal and resiliently held in normal position by means of a coil spring to lock the stanchion in closed position.

A further object is to generally improve 25 and simplify the construction and operation of devices of this character and at the same time reduce the cost of the same.

With this and other objects in view, my 30 invention will be more fully described, illustrated in the accompanying drawings which show a preferred embodiment of my device and then specifically pointed out in the claims which are attached to and form a part of this application.

In the drawings:—Figure 1 is an elevational view of a stanchion equipped with my improved lock. Fig. 2 is a top plan view thereof. Fig. 3 is a similar view with a lock and stanchion in open position. Fig. 4 is a vertical sectional view on the line 40 4—4 of Fig. 1. Fig. 5 is a cross sectional view on the line 5—5 of Fig. 1. Fig. 6 is a detail view of the lock removed. Fig. 7 is a cross sectional view similar to Fig. 5, showing the lock in open position. Fig. 8 is a 45 cross sectional view on the line 8—8 of Fig. 2.

Referring more specifically to the drawings, in which similar reference numerals 50 designate corresponding parts throughout, 10 designates the lower horizontal members and 11 the upper horizontal members of the stanchion frames which horizontal members are connected at their opposite ends by the vertical members 12 having their ends secured by said horizontal members. The movable stanchion bar 13 has its lower end

pivoted between the lower members 10 while its upper end is adapted for movement between the upper or horizontal members 11 and adapted to be locked in position by 60 means of my improved locking mechanism which will now be described.

My improved lock is formed of two pieces 14 and 15 of spring metal preferably of circular form in cross section. The ends of 65 the members or pieces 14 and 15 are provided with the eyes 16 and 17 through which the pivot pin 18 is passed, said pin 18 extending vertically through the front of the member 11 near one end thereof and through the transverse horizontal opening 19 in the member 11, in which opening the eyes 16 and 17 are positioned, the member 14 being positioned in front of the member 11 while the member 15 is rearwardly 70 thereof. Adjacent the eye 16, the member 14 is bent at a right angle and normally engaged against the front face of the outer member 11 and a spaced distance from the opposite end of said member 14, the latter 75 is again bent at a right angle and extended rearwardly through the opening 20 in the member 11 in the path of movement of the outer end of the movable stanchion bar 13, said end terminating in the eye 21 adjacent 80 the rear member 11. The member 14 is provided with an offset portion 22 intermediate its bent ends to form a handle by 85 means of which the lock may be opened, as will later be clearly apparent. Passed 90 through the eye 21 of the member 14 and through the eye 23 on the end of the member 15 opposite the eye 17 is a connecting bolt 24 to connect the members 14 and 15 and the member 15 is provided intermediate 95 its length with a forwardly directed lug portion 25 which is engaged in the opening 26 in the frame member 11, between the openings 19 and 20. A coil spring 27 is engaged around the lug 25, and bears 100 against the plate 28 employed for closing the forward end of the opening 26. The spring 27 serves to resiliently retain the lock members 14 and 15 in the path of movement of the upper end of the movable bar 13, the 105 main portion of the member 14 engaging against the outer face of the member 11 and against the plate 28. To release the member 13, the handle portion or offset portion 22 is engaged and the members 14 and 15 110 swung forwardly upon the pivot pin 18 thus compressing the spring 27 and drawing the

member 15 against the rear face of the member 11, allowing the reduced upper end 13' to ride over the lock member 15.

It will be understood that the reduced upper end 13' of the bar 13 is produced by cutting away a portion of said upper end to allow the bar to properly ride over the lock member 15 when said lock is in open position.

10 It will be understood that when the stanchion is in open position, the upper end of the member 13 will rest between the ends of the members 14 and 15 connected by the pin 18 and the adjacent corner of the frame and 15 the members 14 and 15 will assume their inner or locked position being automatically swung to said position by means of the spring 27.

From the foregoing it will be evident that 20 I have provided a spring stanchion lock of extremely simple construction and operation that will be highly efficient and effective in use. It will also be evident that this lock may be readily and cheaply applied to stanchions now in use. Further it will be evident that minor changes in the details of construction may be made if desired without in the slightest degree departing from the spirit of my invention.

30 What I claim is:—

1. In a stanchion lock, the combination with the upper forward horizontal frame member and the movable stanchion bar, of a forward lock member having one end bent

rearwardly and extended through the frame 35 member and in the path of movement of the movable bar, a rear lock member having its opposite ends connected to the ends of the forward lock member, said lock members being pivoted at one end in the frame member, 40 a lug projecting forwardly from the rear lock member and into the frame member, and means engaged around the lug and pressing against the rear member to resiliently retain the lock in closed position. 45

2. In a stanchion lock the combination with a stanchion frame and movable bar, of a rear lock member having a lug projecting therefrom and the forward member having one end connected with the rear member, 50 said forward and rear lock members being pivoted in the frame at their connected portions, the spring engaged around the lug of the rear member for resiliently retaining said member in spaced relation to the frame, 55 the opposite end of the forward lock member being bent rearwardly and secured to the rear lock member, and means carried by the forward lock member for withdrawing the lock members from the path of movement of the movable bar. 60

In testimony whereof, I affix my signature, in presence of two witnesses.

MILO B. HINER.
